UNITED STATES PATENT OFFICE.

MARK SULLIVAN, JACOB KESSLER, AND JOSIAH R. FOSTER, OF DUBUQUE, IOWA.

WOODEN TRUSS-BRIDGE.

SPECIFICATION forming part of Letters Patent No. 224,491, dated February 10, 1880.

Application filed August 13, 1879.

To all whom it may concern:

Be it known that we, MARK SULLIVAN, JACOB KESSLER, and JOSIAH R. FOSTER, of Dubuque, in the county of Dubuque and State 5 of Iowa, have invented a new and useful Improvement in Wooden Truss-Bridges; and we do hereby declare that the following is a full and exact description of the same, reference being had to the accompanying drawings, and 10 to the letters of reference marked thereon.

The object we have in view is to construct a truss-bridge so that the necessary strength can be obtained with fewer and lighter timbers, and so that the chords, when made of 15 wood, will be preserved from decay at their ends.

Our invention therein consists in the manner of constructing and arranging the flooring-timbers of the bridge so that they will be partly 20 self-supporting, and so that the ends of the straight chords or tie-beams will not have to be buried in earth; and, further, in the peculiar construction of the truss, made without piercing or boring any of the timbers, which 25 enables lighter and fewer timbers to be used than heretofore to obtain the required strength, all as fully hereinafter explained.

In the drawings, Figure 1 is a side elevation of our bridge when made in two sections; 30 Fig. 2, a central longitudinal section of the same; Fig. 3, a similar section through one chord; Fig. 4, a separate view of one of the cap-plates; Fig. 5, a separate view of one of the stirrups; Fig. 6, a side elevation of our bridge when made in three sections; Fig. 7, a 35 sectional view, showing the manner of supporting the three-section flooring; Figs. 8 and 9, views, similar to Figs. 6 and 7, of a bridge having four sections of flooring.

40 Like letters denote corresponding parts.

The bridge having two sections of flooring is built in the following manner: Upon the abutments A are laid the raised corner-stones a, upon which stones rest the ends of the 45 chords or tie-beams B, preferably of wood. By means of the corner-stones a the chords are raised at their ends above the abutments, for a purpose to be presently described.

The inclined braces C on each chord, and 50 forming part of each truss, are beveled at their

lower ends where they rest upon the chord, and are there rigidly secured to the chord by U-shaped stirrups D, which have screw-threaded ends passing through plates D' and secured by nuts b. The stirrups are inclined 55 inwardly at right angles to the line of inclination of the braces, and they rest in grooves c in the under side of the chords, to enable them to resist the strain without sliding upon the chords.

At their upper ends the braces are beveled and rest against each other. No queen-posts are used; but upon the top angle of each pair of braces is placed a cap piece or plate, E. These cap-plates E are made of metal, have 65 angular under faces, d, which fit the angle made by the meeting ends of the braces, strengthening-ribs d' on their upper faces, and extend on each side beyond the braces.

Through each cap-plate, outside of the 70 braces, are passed four rods, F, secured by nuts, which rods extend directly down, passing two on each side of the chord or tie-beam below, and on each side of a central transverse binding-joist, G, and through a plate or 75 crossed straps e, on the under side of such joist G. The rods F are secured by nuts at one or both ends, which are tightened to draw and secure the parts of each truss firmly and rigidly together.

The central binding-joist, G, (which is the 80 only one used in the two-section bridge,) extends transversely beneath both chords and projects on each side beyond such chords.

From the ends of the joist G outside braces, 85 G', extend up beneath the projecting edges of the cap-plates E; but these braces may be dispensed with.

It will be seen that by using the stirrups to bind the ends of the braces, and by using the 90 peculiar cap-plates and outside rods, none of the timbers are pierced by bolts, which weaken the parts very materially, and therefore much lighter timbers can be used to gain the necessary strength; and, also, it will be observed 95 that with our construction no queen-posts are required, which is a saving in timber and makes the bridge lighter.

The longitudinal sills H, to which the flooring of the bridge is secured, are laid upon the 100

joist G with abutting ends, and incline or curve downwardly from such joist to their outer ends, which rest against the abutments and the filling between the corner-stones a.

5. The tops of the sills H are made, preferably, curved, so that there will be a gentle rise from the ends to the center of the bridge.

It will be seen that by this manner of constructing the flooring of a bridge the sills will 10 brace each other, and the abutments will take the thrust independent of the truss, making the flooring partly self-supporting, so that the truss will be greatly relieved from the weight of travel. This double inclination of the floor 15 of the bridge also serves to carry off the water and keep the timbers dry. By this arrangement of the sills the flooring I at the center of the bridge is nearly or quite on a level with the top of the chords, while at its outer ends 20 it is about on a level with the under faces of such chords or the tops of the corner-stones. The approaches to the bridge are built or graded up to the ends of the flooring, but the ends of the chords are not covered at all with 25 earth.

Heretofore in this style of bridge it has been necessary to cover the ends of the wooden chords with earth in grading the approaches to the bridge, which has caused such chords 30 soon to decay, while the other parts of the bridge were in sound condition. With our construction, however, this objection is avoided.

When the width of the stream requires a longer bridge, our bridge can be made in three, 35 four, or more sections. When made in three sections, Figs. 6 and 7, there is placed between the inclined truss-braces C, on each side, a horizontal lengthening truss-beam, K, beveled at its ends, as shown. At the ends of the 40 truss-beam, over the joints with the braces, are placed half cap-plates L, having horizontal and inclined under faces, ll'. These cap-plates extend beyond the sides of the truss braces and beams, and have long rods F extending 45 down to plates or straps e on the under side of

two joists, G. The flooring-sills H', extending between the two joists G, are crowned or curved on their upper sides to preserve the curve of the flooring. No queen-posts are used, and outside braces, G', Fig. 1, may be employed.

For bridges of four or more sections, Figs. 8 and 9, the chords and truss-beams are made proportionately longer, and at one or more points intermediate between the joints at the ends of the truss-beam are placed flat cap- 55 plates m, extending beyond the sides of the truss-beam and secured to rods F, supporting binding-joists below. The floor-sills are curved to give the crown to the flooring of the bridge.

What we claim as our invention is— 60

1. In a wooden truss-bridge, the combination of the truss-frames having straight wooden chords B, resting upon the abutments above the road-filling, one or more transverse binding-joists G, supported below the cords by rods 65 from the braces C of the truss-frames, and the flooring-timbers H, inclined or curved upwardly from the abutments between and below the ends of the chords to such binding joist or joists, whereby the cords are preserved from 70 decay and the flooring-timbers are made partially self-sustaining, substantially as described and shown.

2. In combination, the straight wooden chords, inclined braces secured to the chords by 75 stirrups, angular cap-plates, one or more transverse binding-joists hung from the cap-plates by rods passing down on the outside of the truss-timbers, and the flooring-timbers inclined or curved upwardly from the abutments to the 80 center of the bridge, substantially as described and shown.

This specification signed and witnessed this 23d day of June, 1879.

MARK SULLIVAN.
